FLUID PUMP

Frank H. Johnston and Arthur E. Du Bois, Dayton, Ohio, assignors to Premier Engineering Company, Dayton, Ohio, a corporation of Ohio

Application August 25, 1939, Serial No. 291,860

12 Claims. (Cl. 103—195)

This invention relates to a fluid pump and more particularly to a fluid pump of the vertical type adaptable for use as a shallow well water pump.

An object of this invention is to provide a shallow well water pump that has a satisfactory performance as compared to conventional shallow well pumps now appearing on the market and constructed and arranged so as to be produced from fewer parts with less labor, resulting in a reduction in production cost, thereby reducing the ultimate cost of the pump.

Another object of this invention is to provide a vertical fluid pump of the reciprocating plunger type that is compact, utilizing few parts, simple, efficient, dependable and easily produced.

Another object of this invention is to provide a tubular support or housing that incorporates a vacuum chamber, an air compression chamber, cylinders and a cross head guide portion.

Another object of this invention is to provide a shallow well pump having a pair of cylinders arranged in tandem, one of which may be referred to as the intake cylinder and the other the expulsion cylinder, the cylinders being vertically disposed and located below the cross head.

Another object of this invention is to water cool the cross head guide portions.

Another object of this invention is to provide duo-functional cooling and fluid storage compartments partially filled at cyclic intervals.

Another object of this invention is to provide a unitary casting for supporting the cylinders of the pump and incorporating water storage compartments therein, partially filled cyclically.

Other objects and advantages reside in the construction of parts, the combination thereof, and the mode of operation, as will become more apparent from the following description.

Referring to the drawings,

Figure 1 is a side elevational view of the pump.

Figure 2 is another side elevational view, looking in the direction of the arrow 2 in Figure 1.

Figure 3 is a transverse cross sectional view, taken substantially on the line 3—3 of Figure 4.

Figure 4 is a cross sectional view taken substantially on the line 4—4 of Figure 2.

In the past it has been found impractical to use fluid pumps of the reciprocating piston type, especially for use as shallow well water pumps utilizing vertically disposed cylinders arranged in tandem wherein the power driven means, that is, the cross head, is located immediately above the cylinders. The oil used in lubricating the

cross head has had a tendency to mix with the water, which, of course, is objectionable for obvious reasons. That being the case, practically all, if not all, of the shallow well water pumps now appearing on the market utilizing a reciprocating piston arrangement are of the horizontal type, so as to permit proper lubrication of the power actuating device without any danger of the oil or greases contaminating the water.

In the present embodiment a tubular housing provided with a longitudinal bore has been used, which housing incorporates seats for the cylinders and supports for the eccentric cam driving the cross head. This cross head is mounted for reciprocating movement in guides integral with the tubular member. In addition to the supporting structure for the cylinders and the driving mechanism, this tubular member is provided with laterally disposed chambers, one of which 10 functions as a vacuum chamber and the other as a compression chamber. These chambers are aligned and positioned immediately outside of the guides for the cross head, so that the chambers have a dual function, that is, they function 15 as water storage compartments partially filled with water at cyclic intervals and as water cooling passages for the guide portions. The guide portions are concentrically disposed with respect to the piston rod, but of a larger diameter than the pistons, 20 so that in the event any oil is spilled or slops over, this oil will not drip or flow into the cylinder located directly below the cross head. Instead, it will drip on the outside of the cylinder, where it is caught by a transverse diaphragm connected 25 to the exterior through suitable vents. There is a vent below the diaphragm also, permitting the circulation of air, thereby preventing the piston from operating against a vacuum.

In the drawings, the reference character 10 indicates a tubular frame and housing member provided with a suitable cap or capping member 12, secured in position by suitable studs or bolts. This tubular frame and housing member is provided with a longitudinally extending bore having various widths throughout its length. Capping member 12 supports an electric motor 14 driving a V-belt 16 passing over a pulley 18. The pulley 18 is keyed or otherwise secured to the end of the crank shaft 20 journalled in suitable 45 bearings mounted in the sides of the tubular housing member 10. Within the housing the shaft 20 supports an eccentric cam 22 driving a connecting rod 24 interconnected by a wrist pin 26 to a cup-shaped cross head 28, guided by 50 cross head guide portions 30 integral with mem-

ber 10. The cross head 28 is provided with a pair of channels 32 subtended on the inside by diametrically disposed ribs 34. The channel portions 32 terminate in apertures opening into the interior of the cross head. Suitable oil absorbing wicks 36 are positioned in the channels 32, the ends projecting into the bottom of the cup of the cross head 28. The bottom of the cross head is filled with oil. This oil is supplied to the guide portions 30 by capillary attraction through the wicks 36.

The clearance between the cross head 28 and the guide portions 30 is extremely small, so that the quantity of oil utilized by these parts is practically negligible. It is very desirable that the oil within the cross head 28 last over a long period of time for oiling both the cross head 28, sliding upon the guide portions 30, and the connection between the connecting rod 24 and the wrist pin 26.

In spite of thorough lubrication, friction will generate heat. That being the case, if the heat in the moving parts is not dissipated or carried away, the parts will expand, thereby changing the clearance so as to attract excessive quantities of oil. Therefore, the guide portions 30 are cooled by water advancing into the vacuum chamber 40 and the compression chamber 42 located on the outside of the walls bounding the guide portions 30. These chambers are partially filled with water at cyclic intervals, as will appear more fully from the description of the operation of the pump.

The cross head 28 is connected through a suitable piston rod 50 to a piston or plunger 52 mounted for reciprocatory movement in a cylinder 54, which cylinder is fixedly mounted in tubular housing member 10. The cylinder 54 is preferably made of brass and press fitted into the supporting structure of the frame 10 with the upper edge of the cylinder projecting a slight distance above the supporting structure. A piston interconnecting rod 56, extending from the piston or plunger 52, is connected to a piston or plunger 60 in a cylinder 62 mounted near the bottom of the tubular frame member 10. The piston or plunger 60 is provided with a plurality of water passages which are closed during a portion of the cycle by a cushion valve 64 biased into the "down" position by a spring 66 held in position by a suitable nut 68 threadedly engaging the piston rod 56. The cushion valve 64 has been fully shown and described in the copending application Serial No. 251,920 filed January 20, 1939 for Valve. A check valve 70 of the same type as the one described above is mounted upon a valve seat 72 in member 74 providing a passage between the cylinder 60 and the intake conduit 76. Water is supplied to the pump through an intake pipe 78 and discharged from the pump through an outlet pipe 80. The chambers 40 and 42 are provided with suitable vent plugs 82 and 84.

The inside diameter of the cylinder 54 is selected so that the cross sectional area of the bore in the cylinder 54 is approximately one-half the cross sectional area of the bore in cylinder 62.

A diaphragm 86 extends across the central bore of the housing member 10 below the extreme lowest position of the cross head 28 and above the cylinder 54. This diaphragm 86 is provided with a suitable aperture or passage for the piston rod 50. The aperture in the diaphragm 86 is surrounded by a lip or wiper portion 86a, so that in the event oil drips from the guide portions 30,

these drippings are caught by the diaphragm 86 and conveyed to the exterior of the pump through vents 90, one on either side of the frame member 10. Thus, any oil that may accidentally drip from the guide portions is drained to the exterior of the pump, without entering the cylinders and the water passages. The vents 90, in addition to providing an escape passage for the oil, ventilate the interior of the tubular frame member between the cross head 28 and the diaphragm 86. Vents 92 are also provided in the side of the tubular frame member 10 below the diaphragm 86 and the top of the portion supporting the cylinder 54, so as to provide a ventilation and prevent the formation of vacuum or a compression chamber between the piston 52 and the diaphragm 86.

Suitable covers 94 provided with louvres are used to cover the vents 90 and 92, there being 20 one cover for the vents located on one side of the tubular frame and housing member 10 and another cover diametrically disposed for covering the vents on the opposite side.

25

Mode of Operation

Although reciprocatory plungers or pistons have been used, the pump supplies a continuous flow of water, or substantially so. The intake pipe 78 is connected to a suitable source of water. As soon as the motor circuit is closed, which may be closed manually or automatically, the motor through the belt 16 drives the pulley 18, rotating the shaft 20 and with it the eccentric cam 22. This rotary movement is translated into reciprocatory movement by the connecting rod 24 actuating the cross head 28 propelling the piston rod 50 and with it the piston interconnecting rod 56, which causes the plungers 52 and 60 to 35 reciprocate in their respective cylinders.

As the pistons or plungers move down in unison, the valve 64 is opened and the valve 70 is closed. Upon the reversal of the movement of the pistons when reaching the lower end of 45 the stroke, the valve 64 is closed and the valve 70 sucked open, creating a partial vacuum in the conduit 76, in the vacuum chamber 40 and in the intake pipe 78. When the pistons again reverse the movement, the cycle is repeated. Eventually, 50 sufficient vacuum is created to draw the water into the intake pipe 78, where it is drawn intermittently into a rather large chamber 96, between the pistons 52 and 60. During the "up" stroke, the pistons 60 lift the water into the chamber 96, part of it escaping through the outlet 80, part of the water following the piston 52, so as to fill the open end of the cylinder 54 and 55 part being raised into the air compression chamber 42. The opening to the outlet pipe 80 is preferably such that approximately half of the water lifted during half of the cycle flows through the outlet, the remainder of the water that is lifted being raised into the cylinder 54 and the air compression chamber 42. When the piston 60 has reached the upper end of its stroke and reverses, the valve 70 closes, so as to entrap the water located between the valve 70 and the piston 60, thereby forcing the valve 64 into open position, so that the water in the chamber 96 cannot drop or be lowered with the piston 60; but instead, the piston 52, advancing downwardly in unison with the piston 60 expels the water in the cylinders 54 through the outlet 80. Thus, in spite of a tendency to a pulsating flow of water normally found in shallow well pumps of the recip-

rotatory type, the flow of water from this pump is substantially uniform.

The impact caused by the reversal of the cylinders upon the valves 64 and 70 respectively, is cushioned and practically noiseless, due to the peculiar shape of the feathery edge used on the valves, as fully described in the above identified application. Valves formerly appearing on the market, if used in this pump, would result in a practically useless structure, due to the resultant pounding or hammering noises. Hence, the successful operation of this pump is closely associated with the inventive idea disclosed in the copending application Serial No. 251,920.

This pump, which supplies a substantially continuous flow of water, utilizes only two check valves. In the majority of pumps now appearing on the market used in connection with shallow wells, a double acting piston is used, requiring four valves.

Due to the importance of avoiding leakage of water from the cylinder 54, having the plunger 52 mounted therein, a special type of plunger has been used which includes the following structure. The plunger assembly 52 includes a backing member 52a supporting one side of the pump leather 52b. In order to force the lip of the leather 52b against the walls of the cylinder 54, a rubber ring 52c mounted upon the grooved collar 52d exerts an outward pressure upon the 30 lips of the leather, so as to provide water-tightness. A second leather 52e, having the lip thereof biased outwardly by a rubber ring 52f supported upon a grooved collar 52g, is also used. By this arrangement a double leather plunger 35 has been produced, which plunger is provided with the resilient cushioning members biasing the leathers outwardly against the wall of the cylinder. This arrangement is found very desirable in a pump of this type where the pump 40 is used in dwellings and the like where any leakage from the pump is very undesirable.

In order to facilitate replacement and repairs to the pump, as well as assembly during manufacture, the piston rod 50 is removably attached to the cross head 28. In the particular embodiment shown, the upper end of the piston rod 50 projects into an aperture in the boss 28a integral with the cross head 28. The piston rod 50 is held in position by a transverse pin 98 passing through suitable apertures in the boss 28a and the top of the piston rod 50. The pin is aligned with the vents 90, so that the pin may be removed by merely removing the covers from the vents 90. After repair, the pin may be replaced through the vents 90. By this arrangement it is possible to replace leathers, change valves and the like, without removing the crank shaft, the connecting rod and the cross head. It is merely necessary to remove member 74 after the pin has been removed, at which time the two pistons may be removed from the bottom of the frame member 10.

In the event it should be found desirable to tighten or change the tension of the belt 16, this may be accomplished by adjusting the bolt 100, as clearly shown in Figure 1. Any other suitable bolt adjusting mechanism may be used. The one shown herein has merely been shown for the purpose of illustration of a workable embodiment of the pump.

Although the device has been described as a shallow well water pump or water lift, this pump may be used for other purposes and for pumping other fluids. Likewise, the parts and structural

details have been merely shown for the purpose of illustration and are not intended as limitations.

Although the preferred modification of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. In a power driven shallow well water pump having a cross head, a tubular member provided with a longitudinal bore of varying dimensions forming a pair of aligned cylindrical portions and cross head guide portions, said cross head guide portions being arranged in spaced relation from the cylindrical portions, said tubular member having a pair of duo-functional chambers contiguous to the guide portions, one of which forms an air chamber and the other a vacuum chamber, each partially filled with water at cyclic intervals so as to cool said cross head guide portions, said tubular member being provided with air circulating vents between the cross head guide portions and the adjacent cylindrical portions.
2. In a shallow well water pump, the combination including a power driven cross head, a tubular frame member provided with a longitudinal bore of varying dimensions forming a pair of cylindrical portions and a cross head guide portion, said tubular member having a vacuum chamber contiguous to the cross head guide portion, said vacuum chamber being partially filled with water at cyclic intervals, said tubular member being provided with an air circulating vent intermediate said cross head guide portion and the adjacent cylindrical portion, pistons mounted in the cylindrical portions for reciprocating movement, and a piston rod for interconnecting the cross head to the pistons, said tubular member having a diaphragm disposed intermediate the guide portion and the adjacent cylindrical portion, said diaphragm being provided with a passage through which the piston rod extends.
3. In a power driven fluid pump, a cylindrical member provided with a longitudinal bore of varying dimensions forming a pair of cylindrical portions and cross head guide portions, said portions being arranged in tandem, said cylindrical member having a pair of duo-functional chambers contiguous to the guide portions forming an air chamber and a vacuum chamber partially filled with fluid at cyclic intervals so as to control the flow of fluid motivated by the pump and to maintain the cross head guide portions at a substantially uniform temperature.

4. In a power driven water pump the combination including a vertically disposed cast cylindrical frame member provided with a longitudinal bore varying in diameter, said bore including a cylindrical portion, a piston in said cylindrical portion, a pair of cross head guide portions arranged in spaced relation from the cylindrical portion, said cylindrical frame member including a vacuum chamber for cooling one of the guide portions, said vacuum chamber having an opening in association with the intake of the pump, a compression chamber in association with the other guide portion, said compression chamber opening into the outlet of the pump, an apertured diaphragm extending across the bore of

said cylindrical frame member between the guide portions and the cylindrical portion, a connecting rod passing through the aperture in said diaphragm, a cross head guided for reciprocatory movement by said guide portions, and a piston rod extending through the aperture in the diaphragm for connecting the cross head to said piston so as to cause the piston and the cross head to reciprocate in unison.

5. In a power driven water pump the combination including a vertically disposed cast cylindrical frame member provided with a longitudinal bore varying in diameter, said bore including a pair of cylindrical portions arranged in tandem, a pair of pistons, one in each of said cylindrical portions a cup-shaped cross head having an oil cavity, a pair of guide portions arranged in spaced relation from the cylindrical portions for guiding the cross head, said cylindrical frame member including a pair of duo-functional water chambers one for each of the guide portions for cooling the same, an apertured diaphragm extending across the bore of the cylindrical frame member between the guide portions and the adjacent cylindrical portion, a connecting rod passing through the aperture in said diaphragm, and means for oiling the cross head, said means including a fibrous member for supplying oil by capillary attraction from the cavity in said cup-shaped cross head to the guide portions.

6. In a power driven shallow well type water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having slots in the wall thereof, said cross head being provided with an oil cavity, a pair of guide portions located above the cylindrical portions for guiding the cross head, the distance between the guide portions being greater than the diameter of the adjacent cylindrical portion, said cylindrical frame member including a pair of duo-functional water chambers one for each of the guide portions for cooling the same, means for interconnecting the cross head and the pistons, and means for oiling said cross head guide portions, said means including fibrous members for supplying oil by capillary attraction from the cavity in the cup-shaped cross head through the slots in the wall thereof to the guide portions.

7. In a power driven shallow well type water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having slots in the wall thereof, said cross head being provided with an oil cavity, a pair of guide portions located above the cylindrical portions for guiding the cross head, the distance between the guide portions being greater than the diameter of the adjacent cylindrical portion, said cylindrical frame member including a pair of duo-functional water chambers one for each of the guide portions for cooling the same, means for interconnecting the cross head and the pistons, means for oiling said cross head guide portions, said means including fibrous members for supplying oil by capillary attraction from the cavity in the cup-shaped cross head through the 75

slots in the wall thereof to the guide portions, and means disposed intermediate the guide portions and the adjacent cylindrical portion for catching oil dripping from the guide portions.

5. 8. In a power driven water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having an apertured side wall, said cross head having an oil cavity, a pair of guide portions located above the cylindrical portions for guiding the cross head, a crank shaft, a crank arm for interconnecting the crank shaft to the cross head, the crank arm being pivotally attached to the cross head near the bottom of the cavity below said apertures in the wall of the cross head, said cylindrical frame member including a pair of duo-functional water chambers one for each of said guide portions for cooling the same, means for oiling said guide portions by capillary attraction from oil in the cavity in said cup-shaped cross head through the apertures in the wall thereof to the guide portions, and means for preventing the oil dripping from the cross head from entering the adjacent cylindrical portion, said means draining the dripping oil to the exterior of the pump.

9. In a power driven water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having apertured side walls, said cross head having an oil cavity, a pair of guide portions located above the cylindrical portions for guiding the cross head, a crank shaft, a crank arm for interconnecting the crank shaft to the cross head, the crank arm being pivotally attached to the cross head near the bottom of the cavity below said apertures in the wall of the cross head, said cylindrical frame member including a pair of duo-functional water chambers one for each of said guide portions for cooling the same, means for oiling said guide portions by capillary attraction from oil in the cavity in said cup-shaped cross head through the apertures in the wall thereof to the guide portions, and an apertured diaphragm extending across the bore below the guide portions and above the upper cylindrical portion, said diaphragm having an upwardly directed rib surrounding the aperture therein, said diaphragm being associated with a drainage duct for draining the oil dripping upon said diaphragm from said guide portions to the exterior of the pump.

10. In a power driven shallow well type water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having an oil cavity, a pair of guide portions arranged in spaced relation from the cylindrical portion for guiding the cross head, an apertured diaphragm extending across the bore of the cylindrical frame member between the guide portions and the adjacent cylindrical portion, duo-functional water chambers, one for each of the guide portions, for cooling the guide portions, each of said chambers being connected

to said bore by a water passage, a connecting rod passing through the aperture in said diaphragm, and means for oiling the cross head, said means including a fibrous member for supplying oil from the cavity in said cup-shaped cross head to the guide portions by capillary attraction.

11. In a power driven shallow well type water pump the combination including a vertically disposed cast cylindrical frame member provided with a longitudinal bore varying in diameter, said bore including a pair of cylindrical portions arranged in tandem, a pair of pistons one in each of said cylindrical portions, a cup-shaped cross head having slots in the wall thereof, said cross head having an oil cavity, a pair of guide portions located above the cylindrical portions for guiding the cross head, the distance between the guide portions being greater than the diameter of the adjacent cylindrical portion, duo-functional water chambers, one for each of the guide portions, for cooling the guide portions, each of said chambers being connected to said bore by a water passage, means for interconnecting the cross head and the pistons, and means for oiling said cross head guide portions, said means including fibrous members for supplying oil from the cavity in the cup-shaped cross head through the slots in the wall thereof to the guide portions by capillary attraction.

12. In a power driven shallow well type water pump the combination including a vertically disposed cast cylindrical frame member provided with a longitudinal bore varying in diameter, 5 said bore including a pair of cylindrical portions arranged in tandem, a pair of pistons one in each of said cylindrical portions, a cup-shaped cross head having slots in the wall thereof, said cross head having an oil cavity, a pair of guide portions located above the cylindrical portions for guiding the cross head, the distance between the guide portions being greater than the diameter of the adjacent cylindrical portion, duo-functional water chambers, one for each of the 10 guide portions, for cooling the guide portions, each of said chambers being connected to said bore by a water passage, means for interconnecting the cross head and the pistons, means for oiling said cross head guide portions, said means including fibrous members for supplying oil from the cavity in the cup-shaped cross head through the slots in the wall thereof to the guide portions by capillary attraction, and means disposed intermediate the guide portions and the 15 adjacent cylindrical portion for catching oil dripping from the guide portions.
